	1231	1232	1233	1234	1235	1236	1237	1238	1239	1240	1241	1242	1243	1244	1245	1246	1247	1248	1249	1250	1251	1252	1253	1254	1255	1256	1257	1258	1259	1260	1261	1262	1263	1264	1265	1266	1267	1268	1269	1270	1271	1272	1273	1274	1275	1276	1277	1278	1279	1280	1281	1282	1283	1284	1285	1286	1287	1288	1289	1290	1291	1292	1293	1294	1295	1296	1297	1298	1299	1300	1301	1302	1303	1304	1305	1306	1307	1308	1309	1310	1311	1312	1313	1314	1315	1316	1317	1318	1319	1320	1321	1322	1323	1324	1325	1326	1327	1328	1329	1330	1331	1332	1333	1334	1335	1336	1337	1338	1339	1340	1341	1342	1343	1344	1345	1346	1347	1348	1349	1350	1351	1352	1

UNITED STATES PATENT OFFICE.

JOSEPH KOENEN, OF MILWAUKEE, WISCONSIN.

ROUTE-BOOK.

1,161,482.

Specification of Letters Patent. Patented Nov. 23, 1915.

Application filed November 13, 1911. Serial No. 659,941.

To all whom it may concern:

Be it known that I, JOSEPH KOENEN, a citizen of the United States, and resident of Milwaukee, in the county of Milwaukee and 5 State of Wisconsin, have invented new and useful Improvements in Route-Books, of which the following is a description, reference being had to the accompanying drawings, which are a part of this specification.

10 This invention relates to improvements in route books.

It is one of the objects of this invention to provide a route book which is particularly adapted for use in commercial houses 15 to provide a means for ready reference, to indicate the cities of the territory covered by the different salesmen of the house and to also indicate the order in which the cities are visited.

20 A further object of the invention is to provide a route book with leaves having means for detachably holding cards upon which are inscribed the names of the cities in consecutive order that are to be visited 25 by the salesmen or upon which can be inscribed numbers to indicate the consecutive order in which the cities are to be visited when names of cities are alphabetically inserted on leaves.

30 A further object of the invention is to provide a route book with index leaves having means for detachably holding cards upon which are inscribed the names of the traveling men and the number of the route 35 they travel.

A further object of the invention is to provide a route book with leaves having tabs projecting therefrom upon which are inscribed the numbers of the pages, and each 40 number of which is also adapted to designate the number of a particular route or a part thereof.

A further object of the invention is to provide a route book in which the names of 45 the salesmen and the cities may be easily changed from time to time, as required.

A further object of the invention is to provide a route book which is strong and durable and is inexpensive to manufacture.

50 With the above and other objects in view, the invention consists of the improved route book and its parts and combinations, as set forth in the claims, and all equivalents thereof.

55 In the accompanying drawing in which the same reference characters indicate the

same parts in all of the views: Figure 1 is a perspective view of the improved route book with the cover in open position; Fig. 2 is a top view of the route book with the 60 cover in open position and with a portion of one of the index leaves removed; and Fig. 3 is a longitudinal sectional view of a portion of one of the leaves.

Referring to the drawing the numeral 5 65 indicates the covers of the route book and 6 the back thereof to which the improved route leaves 7 and the index leaves 8 are bound in any desirable manner. The book may be in the form of a loose leaf book as 70 shown, or the leaves may be permanently bound to the cover portion in any manner desired.

The route leaves have vertically extending 75 parallel strips of binding 9 sewed to opposite sides thereof by medial lines of stitching 10, and horizontally extending parallel lines of stitching 11 extending transversely across the said binding strips, form a plurality of card pockets 12 into which indicating town cards 13 are inserted. The medial lines of stitching 10 of the binding permit the ends of the cards to be inserted beneath the free side edges of the binding strips by slightly bending the cards and 80 when the cards straighten out they will be 85 securely held in position.

Each card is adapted to have the name 14 90 of a State and town or city written thereon and also a numeral, 15, to indicate the order 95 in which the cities are to be visited, and are alphabetically arranged with relation to the names of the cities.

All of the town cards of a particular route 100 are placed on the same page or two, depending upon the length of the route, and a card 16, bearing the name of the traveling man having the route, is inserted in one of the upper pockets of the same page. Each 105 page is provided with a projecting index tab 17, having the number of the page or route indicated thereon, and these tabs are adapted to be numbered in consecutive order for convenient reference. The index leaves 8 are also provided with vertically extending binding strips 18 sewed thereto by medial lines of stitching 19 and with horizontal lines of stitching 20 to form pockets 21 into which name cards 22 are inserted in the same manner as the town cards. These 110 name cards have inscribed thereon the names and addresses 23 of the traveling

men and are also numbered as at 24 to indicate the number of the particular route or page assigned to the man. The town leaves may also be provided with cards 25 to indicate that the places named on the cards within the same column are to be visited quarterly, or semi-annually, and these cards are thus inscribed.

In use the different cards are placed in 10 the manner shown and described, and if it is desired to find out the territory covered by a certain salesman it is only necessary to find the name of the salesman among the index cards and to look at the number or 15 numbers of the route inscribed thereon and then turn to the corresponding tab numbers of the route leaves. The leaf of the particular tab indicated will show the names of the different cities visited by the salesman 20 and the consecutive order in which they are visited. When it is desired to change the cities of a route, or change the name of the salesman, it is only necessary to remove a card and substitute another card therefor. 25 From the foregoing description it will be seen that the route book is well adapted for the purpose desired.

What I claim as my invention is:

1. A route book, comprising route leaves 30 provided with means for detachably holding cards and also having index characters, cards detachably connected to said leaves and having the names of municipalities inscribed thereon, an index leaf provided with 35 means for detachably holding cards, and cards detachably connected to said index leaf and having index characters similar to the index characters of associated route leaves, and also having the names of sales- 40 men inscribed thereon who travel over the territory inscribed on the cards mounted on the route leaf or leaves associated with the index leaf related thereto.

2. A route book, comprising route leaves 45 provided with means for detachably holding cards and also having index tabs projecting therefrom which have index characters inscribed thereon, cards detachably connected to said leaves and having the names of municipalities inscribed thereon, an index leaf provided with means for detachably holding cards, and cards detachably connected to said index leaf and having index characters similar to the index characters of associated route leaves, and also having the names of salesmen inscribed thereon who travel over the territory inscribed on the cards mounted on the route leaf or leaves associated with the index leaf related thereto.

associated with the index leaf related thereto. 60

3. A route book, comprising route leaves provided with parallel strips of binding sewed medially throughout their lengths to the leaves and also having parallel lines of stitching extending at right angles to the strips to form card pockets, said leaves also provided with index tabs projecting therefrom which have index characters inscribed thereon, cards removably inserted within said pockets and having the names of municipalities inscribed thereon, an index leaf forming part of said book and being of less width than the other leaves and provided with strips of binding sewed thereto and with transverse lines of stitching to 75 form pockets, and name cards removably inserted in said last mentioned pockets, said name cards having index characters similar to the index characters of associated route leaves, and also having the names of salesmen inscribed thereon who travel over the territory inscribed on the cards mounted on the route leaf or leaves associated with the index leaf related thereto. 80

4. A route book, comprising route leaves 85 provided with parallel strips of binding sewed medially throughout their lengths to the leaves and also having parallel lines of stitching extending at right angles to the strips to form card pockets, said leaves also 90 provided with index tabs projecting therefrom which have index characters inscribed thereon, cards removably inserted within said pockets and having the names of municipalities inscribed thereon and also having characters inserted thereon which indicate a predetermined successive order, an index leaf of less width than the other leaves forming part of said book and provided with strips of binding sewed thereto and with 100 transverse lines of stitching to form pockets, and name cards removably inserted in said last mentioned pockets, said name cards having index characters similar to the index characters of associated route leaves, and also having the names of salesmen inscribed thereon who travel over the territory inscribed on the cards mounted on the route leaf or leaves associated with the index leaf related thereto. 105

In testimony whereof, I affix my signature, in presence of two witnesses.

JOSEPH KOENEN.
